CHAIR CONSTRUCTION

Filed June 7, 1928

UNITED STATES PATENT OFFICE

FRANK F. FORTNEY, OF BEDFORD, OHIO, ASSIGNOR TO THE B. L. MARBLE CHAIR COMPANY, OF BEDFORD, OHIO, A CORPORATION OF OHIO

CHAIR CONSTRUCTION

Application filed June 7, 1928. Serial No. 283,498.

This invention relates to a chair construction and is particularly adapted for use in connection with chairs of the "spring-back" type commonly used in offices and other 5 places.

In the "spring-back" type of chair, as is well known, the chair back is arranged to move or tilt relatively to the chair seat, the back being held in and returned to its normal 10 position by a substantial spring tension. Frequently the clothing or fingers of the occupant of the chair get inserted between the seat and the back when the latter has been moved or tilted relative to the former, so that 15 they are caught or pinched between these members when the chair back is returned to its normal position by the substantial spring tension, thereby either damaging the clothing or inflicting painful injury to the fingers.

20 The main object of the present invention is to provide a construction for the "spring-back" type of chair wherein all possibility of catching the clothing or pinching the fingers between the seat and chair back will 25 be obviated.

Another object is to provide in a chair of this type a seat and back so constructed and relatively arranged that during the return movement of the back to normal position after 30 having been opened the fingers will be pushed out from between the seat and back.

Additional objects and advantages inherent in the construction will become apparent as the following detailed description 35 of a preferred embodiment of the invention is set forth.

In the drawings—

Fig. 1 is a perspective view of a "spring-back" chair embodying the invention;

40 Fig. 2 is a side elevation thereof;

Fig. 3 is a top plan of the chair seat and a horizontal section of the back taken on line 3—3 of Figs. 1 and 2; and

45 Fig. 4 is a fragmentary view similar to Fig. 3, showing one of the back posts in the open position.

The invention is applicable to any chair construction wherein the chair back is capable of movement relative to the chair seat, so 50 that the particular arrangement or structure

of the mechanism for accomplishing this purpose is immaterial so far as the invention is concerned. Therefore, the description of this part of the embodiment illustrated will be general in character, since its characteristics are well understood in the art. 55

Briefly, the chair shown in the drawing comprises a base formed of four downwardly and outwardly extending or radiating legs 10, which are secured at their upper ends to 60 a common member 11 including an interiorly threaded vertical bushing having an annular flange 12 at its upper end overlying the tops of the legs. Suitable casters 13 are removably or otherwise secured to the lower ends 65 of the legs 10 so that the chair may be readily moved about, as is common practice. It should be here understood that the chair base shown and just described is illustrative only, and that any other type of base might be used. 70

The chair seat 14, which may have its upper surface formed in the usual way so as to provide a comfortable seat, is secured on its under side to a supporting member 15, projecting downwardly from which are a plurality of spaced arms or brackets 16 which provide a support for the mechanism by which the seat is connected to the base and the chair back to the seat. The usual externally threaded downwardly extending screw 75 80 17 is suitably connected to the brackets and is adapted to fit the internally threaded bushing of the base and to be screwed inwardly or outwardly of the same by the nut or collar 18 to vary the height of the chair, all of which is 85 well understood.

The chair back in the present instance comprises the substantially vertical post members 19 which extend below the chair seat and the substantially horizontal members 20 and 21 90 connecting the vertical members at their upper ends and intermediate their ends, such horizontal members in turn being connected by spaced vertical slats 22. Of course, the chair back is suitably curved or formed to 95 most advantageously and comfortably fit the back of the occupant of the chair, as is usual in chair constructions.

As already mentioned, the vertical post members 19 extend below the chair seat on 100

each side of the rear edge thereof, such extending portions of these members being secured to a transversely extending horizontal supporting bar 23 which is operatively associated with a movable spring tensioned member 24. If desirable, means, indicated generally at 25, may be provided for effecting an initial angular adjustment of the seat back.

The spring tensioned member 24 is preferably in the general nature of a bell crank pivotally connected at the junction of its arms to the supporting member 15, the longer of its arms being connected to the bar 23 while the shorter arm 26 extends downwardly and is provided with an opening through which a screw rod 27 passes. This rod is threaded into a portion of the brackets 16 at its inner end while its outer end is provided with a flanged sleeve 28 having a hand wheel 29. A spring 30 surrounds the rod between the arm 26 of the bell crank and the flange of the sleeve, so that when the hand wheel 29 is rotated the spring tension may be increased or diminished. So far the description has related to a conventional construction and it is because of such fact that it has been briefly stated. However, sufficient structure has been described to indicate the manner in which the chair back is movably arranged under spring tension relative to the chair seat.

Heretofore in chairs of this type it has frequently happened that the occupant of the chair has placed his hands or fingers between the rear edge of the chair seat and the back when the latter has been moved out of its normal position and has received painful injury when the back returns to normal position. In a like manner clothing has been caught between the back and seat with the result that the same has been torn when the occupant left the chair. In attempting to obviate these disadvantages guards of various forms have been employed, all of which, however, are unsightly and otherwise unsatisfactory.

Heretofore, attempts to eliminate these disadvantages have been made by recessing the seat edge adjacent to the back and thereby providing a clearance; but, in order to maintain the chair seat and back in the proper relationship the clearance has been insufficient at some point for the purpose desired. Therefore, the present invention contemplates the effective elimination of these disadvantages without changing the relationship of the seat and back. The edge or periphery of the chair seat is provided with recesses 31 adjacent the rear of the seat at approximately the points where the chair back or chair back posts are normally in close contact therewith, the seat edge of these recesses being of a peculiar contour and cooperating with the seat back or back posts in such manner, that not only is it impossible to insert the fingers

at any point where they may be pinched but also the movement of the back to normal position will push or cam the fingers to a safe position. In order to obtain this result the edge of the seat defining the recesses is formed at its forward portion in a substantial curve while at its rearward portion it is formed on a lesser curve, and the seat back or back posts 19 are so arranged that their front faces 32 are at such an angle to the seat edge of the recesses that they will serve or act in conjunction with the seat edge as a cam during the forward movement of the posts to push the fingers into a safe position. Since the corner edges 33 of the back posts, which are adjacent to the seat edge along the lesser curve of the recesses, are positioned so close to such edge that it is impossible to insert the fingers fully therebetween, it is apparent that forward movement of the back will cause the front faces 32 of the posts to cam or push the fingers along the seat edge until they are in the large clearance zone between the front faces and the substantial curve of the seat edge. In Fig. 4 of the drawing the normal and the open positions of the chair back posts 19 are clearly shown, and it is evident that the fingers cannot at any time be placed in a position to be pinched since the forward movement of the posts always push them into the safe position, while at the same time, because of the closeness of the corner edge 33 of the posts and the edge of the seat, the proper relationship between the seat and back is maintained.

Although a preferred embodiment of the invention has been shown and described, it should be understood that the same is not limited thereto but is susceptible of such variations and modifications as fall within the scope of the appended claims.

Having thus described my invention, what I claim is:

1. A chair construction of the type described comprising a seat member, and a back member adapted to be movably associated therewith under spring tension and having post portions normally lying adjacent the edges of the seat so that the seat and back are in the proper relative positions, said seat being provided with recesses adjacent the post portions, and said post portions being disposed so that a substantial clearance space is provided between the edges of the recesses and the front face of each post portion when the seat and back are in the normal position, the edges of the recesses and the front face of each post portion being so arranged as to cooperate to effect a cam action during forward movement of the back to normal position, whereby the fingers of the chair occupant will be pushed into the said clearance space.

2. A chair construction of the type described comprising a seat having its edges

recessed adjacent the rear of the seat and substantially on opposite sides thereof, and a back movably associated under spring tension with said seat, said back having post portions normally lying partly within said recesses, said post portions being so disposed that a substantial clearance space is provided between the front face of each post portion and the edge of the adjacent recess while

5 the inner forward corner of each post portion is closely adjacent the seat edge so that the fingers of the chair occupant can not be placed therebetween, the edges of the recesses and the front face of each post portion being

10 so arranged as to cooperate to effect a cam action during forward movement of the back to normal position, whereby the fingers of the chair occupant will be pushed into the said clearance space.

15

20 In testimony whereof, I hereunto affix my signature.

FRANK F. FORTNEY.
